UNITED STATES PATENT OFFICE.

CHARLES R. KEERAN, OF CHICAGO, ILLINOIS, ASSIGNOR, BY MESNE ASSIGNMENTS, TO AUTOPOINT MANUFACTURING COMPANY, OF CHICAGO, ILLINOIS, A CORPORATION OF ILLINOIS.

PENCIL.

Application filed January 22, 1918. Serial No. 213,241.

To all whom it may concern:

Be it known that I, CHARLES R. KEERAN, a citizen of the United States, residing at Chicago, in the county of Cook and State 5 of Illinois, have invented certain new and useful Improvements in Pencils, of which the following is a specification.

This invention relates to a pencil equipped with propelling mechanism interiorly of its 10 body, and operable by means exteriorly thereof, for advancing into operative position a lead at one end, and an eraser at the other.

Similar pencil constructions are described 15 and claimed in Letters Patent to Keeran Nos. 1,372,354, March 22, 1921, and 1,441,000, Jan. 2, 1923, the applications for which were copending herewith.

For its objects my invention aims to provide 20 an improved and simplified lead propelling mechanism; to use the same mechanism for propelling an eraser; to accommodate in the pencil body a relatively long lead; to provide a magazine of ample capacity 25 for reserve leads; to devise a combined lead and eraser propelling mechanism capable of use, without modification, with a pencil of the non-magazine type; and generally to strengthen the construction, reduce 30 the number of parts, and cheapen the cost of manufacture, of the pencil. These, as well as other objects which will presently appear, are clearly set forth in the appended specification and claims, wherein reference 35 is made to certain embodiments of my invention as illustrated in the accompanying drawings in which—

Figure 1 is a longitudinal section through 40 a pencil of the magazine type, the parts being shown in their relation to a full length section of lead ready for use;

Fig. 2 is a similar view, the parts being shown in their relation to a stub section of lead which has been advanced to its limit;

Fig. 3 is a view similar to Fig. 1, excepting that it shows a pencil of the non-magazine type;

Fig. 4 is an enlarged transverse section taken on line 4—4 of Fig. 1;

Fig. 5 is an enlarged transverse section taken on line 5—5 of Fig. 3;

Fig. 6 is an end view of a detached partition member, such as is shown in Fig. 4;

Fig. 7 is an enlarged fragmentary view showing in longitudinal section the eraser 55 propelling parts, the eraser in this view being full length;

Fig. 8 is a view similar to Fig. 7 showing the relation of the eraser propelling parts when the eraser has just been advanced; 60

Fig. 9 is a view similar to Fig. 8 showing the relation of the parts after the propelling plunger has been retracted;

Fig. 10 is an enlarged detail in longitudinal section of certain parts intermediate the 65 ends of the pencil;

Fig. 11 is a detail in longitudinal section of the lower end of the rotatable sleeve; and

Figs. 12 and 13 are details in section and elevation respectively, of the upper end of 70 the core.

In the use which will hereafter be made of the terms "upper" and "lower", it should be understood that reference is being made to the pencil as it is pointed in use—that 75 is, with the eraser end up, and the writing end down.

The body of the pencil illustrated in Figs. 1 and 2 consists of a cylindrical casing 20, its lower end 21 being tapered. Situated 80 centrally within the pencil is a hollow core 22 having its lower end 23 projected through the tapered end of the casing. In practice I prefer to form an annular shoulder 24 near the core extremity, as shown, adapted to 85 abut the lower end of the pencil taper when the parts are finally assembled.

Surrounding the core 22 is a tube 25 whose outside diameter is slightly reduced in the region of its lower end, thus providing 90 a shoulder 26 against which abuts a circular brace plate or washer 27, the extremity of the tube 25 being beveled as at 28 where it meets with the inner side of the pencil taper. This tube is of slightly reduced internal diameter commencing with a shoulder 29 formed about midway of its length, and from that part upward encases a hollow sleeve 30, whose inner diameter is approximately the same as that of the core 100 22. This inner sleeve 30 is provided at its lower end with a few threads 31 which project into its bore (see Fig. 11). Arranged within the tube 25 and core 22 is a plunger 32 having threads for the greater part of 105 its length adapted to mesh with the sleeve

Fig. 6 is an end view of a detached partition member, such as is shown in Fig. 4;

threads 31, and provided near its lower end with a laterally projecting fin 33 adapted to lie within a slot 34 formed in the core and extending from its upper end nearly 5 to the pencil extremity. The tip end of the core which emerges through the tapered end of the pencil is slightly contracted to frictionally engage the lead as it is propelled therethrough so as to hold the same 10 firmly. The upper end 35 of the core, best shown in Fig. 13, is preferably slanted across, the walls being then beveled inwardly. When assembled (see Fig. 10), the outer edge of the core end at its highest 15 point is situated slightly beneath the shoulder 29. The purpose of this arrangement is (1) to prevent the plunger or a new lead when inserted from lodging against the core end when either is inserted into the 20 pencil, and (2) to present a deflecting surface to the fin 33 such as to cause the plunger to be turned until the fin is aligned with the slot 34 and can enter therein.

Between the tube 25 and the inner sides 25 of the casing is an annular space which may be used as a magazine for storing a reserve supply of leads. In the construction shown, I prefer to divide this magazine space into four compartments, and for 30 this purpose I employ four partition members each designated generally by the numeral 36 and consisting of two radially disposed portions 37 connected by an arc shaped portion 38 (see Fig. 6). These partition members may extend from near the upper end of the pencil casing where it is inset and threaded as at 39 down to the point where the tapered end 21 commences. In practice I prefer to form these partition 40 members of some material that is light, thin, and slightly resilient, such, for instance, as aluminum, so that they may be sprung into place and be held firmly against movement by their own spring action. 45 The parts thus far described include the principal operating elements for propelling the lead through the pencil. In assembling, the brace plate or washer 27 is adjusted on the tube 25 which is next inserted in the 50 casing, the core 22 is then introduced through the pointed end of the casing, and made fast to the tube 25, and the partition members are thereafter sprung into place. By this operation, the plate 27 is likewise 55 forced against the tapered walls of the pencil, so that in this manner these parts become firmly positioned in operative relation. The several partition members, besides affording a desirable support for the 60 leads in the magazine, serve also to maintain the tube 25 centrally within the casing. It is to be understood, of course, that solder or other appropriate means may be used additionally, if desired, to securely hold the 65 parts against displacement.

The description thus far deals only with the structures shown in Figs. 1 and 2 wherein I have provided within the hollow casing a magazine for reserve leads. The present invention is susceptible of use, however, in connection with a non-magazine type of pencil, having a body of wood, hard rubber, fibre, or the like. Such a pencil is represented in Fig. 3. In this construction, the body designated as 40 is provided with 70 a central bore adapted to receive a core 22, non-rotatably secured therewithin by a friction fit or otherwise, a ferrule 41 reinforcing the tip end of the pencil where the core emerges therefrom. A sleeve 30 is rotatably positioned in the upper end of the pencil body having internal threads 31 adapted to mesh with the threads of a plunger 32 in a manner similar to that already described in connection with Figs. 1 and 2. 80 The upper end of the pencil body is likewise inset and threaded as at 39, the same as in the construction of Figs. 1 and 2, the purpose whereof will presently more fully appear. 90

Referring more particularly to Figs. 7, 8, and 9, it will be noted that I have shown in enlarged detail views the arrangement of the parts which constitute the eraser propelling mechanism. As already explained 95 the upper end of the casing may be inset and threaded as at 39 to receive thereon a threaded collar 45 whose upper edge is flanged inwardly as at 46. When assembled in this manner the exterior surface of the 100 pencil is maintained even and smooth at the point of connection between the collar and casing. Rotatably connected with the collar is a bushing 47 having a head 48 at its lower end arranged to underlie the inturned upper edge 46 of the collar, and formed with a boss 49 within which the upper end of the rotatable sleeve 30 is securely held. A sleeve 50 is fastened upon the outer surface of the bushing 47, its upper end being preferably 105 inturned to provide a gripping flange 51 which engages with an eraser 52, the lower end of the sleeve being adapted to rest upon the upper side of the flange 46 on the collar 45. It will be understood that the sleeve 50 and bushing 47 are inseparably connected 110 so that they are rotatable as a unit and with independence of the collar 45, to thereby cause rotation of the sleeve 30 within the pencil body. The sleeve 50, however, together with its associated parts, which may be termed the head of the pencil, is readily 115 detachable therefrom whenever desired. 120

The inner surface of the bushing 47 is formed with threads to receive a threaded eraser plate 53 adapted, when revolved within the bushing, to advance longitudinally therewithin. The upper face of this eraser plate is formed with a slot 54 capable of receiving an instrument when the eraser 125

has been propelled out of its retaining means, so as to enable the operator to rotate the plate and thereby retract the same to the position shown in Fig. 7. The lower face 5 of the plate is provided with a socket 55 internally threaded to receive the upper end of the threaded plunger 32 when the plunger is retracted upwardly a sufficient distance for this purpose.

10 The operation of advancing the lead is apparent from the description hereinbefore contained, it being obvious among other things, that the rotatable sleeve 30 will be turned when the sleeve 50 on the pencil head 15 is revolved. When so actuated, the plunger will move up or down within the pencil according to the direction in which the head sleeve 50 is rotated. If the plunger be propelled downwardly, a lead contained within 20 the core will be propelled through the pencil to advance its point into writing position as far as desired. If the plunger be advanced in the opposite direction, it will withdraw from the lead and present its upper 25 end to the threaded socket 55 of the eraser plate 53. As the pencil head is revolved further, the upper end of the plunger is threaded into the socket 55 for its full depth, and when this point is reached, the plunger 30 and plate are connected so as to advance the plate within the head to propel the eraser. Having advanced the eraser a desired distance, the sleeve 50 may be revolved in the 35 opposite direction, this action causing the plunger to withdraw its end from the socket 55, leaving the plate 53 in advanced position against the eraser, as shown in Fig. 9. This 40 operation may be repeated as often as desired, until the eraser is used up. Any convenient instrument, such as a knife, may then be inserted into the slot 54 on the upper face of the plate to turn the plate back again into its lowermost position, as indicated in Fig. 7, where it is ready to receive a new 45 eraser.

Whenever it is desired to insert into the pencil a new length of lead, the collar 45 is unscrewed from the upper end of the pencil body, and is then removed therefrom, together with the tube 30, and plunger 32 50 therein; at such a time a lead may be inserted into the axial opening of the pencil normally occupied by the tube 30, and under the action of gravity it tends to drop down 55 past the beveled upper end of the core 22 until it lies wholly within the lower portion of the pencil abutting the end of the stub section of lead previously in use, or in frictional engagement with the constricted tip 60 end of the pencil. The tube 30, together with the plunger 32, is then reinserted, the plunger fin being deflected by the slanting upper end 35 of the core 22 so as to enter 65 within the slot 34. The collar 45 is lastly screwed in place and this completes the

reassembling of the parts, permitting them to again function.

The present pencil is designed to accommodate leads much longer than those generally used in mechanical pencils, and the 70 magazine is likewise constructed so as to accommodate an unusually large number of leads. The provision of the partition members not only serves to strengthen the construction, but it also causes the leads to be 75 aligned in circular relation, as best shown in Fig. 4, this arrangement preventing jamming of the leads within the magazine. A special advantage is also realized by the use of the plate 27 which serves the double 80 function of a bottom for the magazine and of a brace to prevent denting of the casing in the region of the upper end of the taper, where damage of this kind is most likely to occur.

Throughout the several figures of the drawings, it will be understood that the same or similar parts are designated by the same reference numerals, even where detailed description may have been omitted for the sake 90 of brevity. It should also be perceived that several distinct inventions have been herein disclosed, such, for example, as the lead propelling mechanism, the eraser propelling mechanism, the magazine construction, the 95 connections between the assembled parts, etc. Several, or all, of these features may be employed in combination, or separately, if desired.

I claim:

1. A pencil having in the lower portion of its body a slotted core, a tube surrounding the core and extending into the upper portion of the body, a threaded sleeve mounted for rotation within the tube above 105 the core, and a threaded lead propelling plunger adapted to travel through the sleeve and core with rotation of the sleeve, the plunger being provided with a projecting element arranged to lie within the core slot 110 to prevent rotation of the plunger relative to the core, the upper end of the core being formed to turn the plunger properly for aligning its projecting element with the slot 115 therein, substantially as described.

2. A pencil having in its body lead propelling mechanism, including in combination a tube within the body provided interiorly with means which present a groove for a portion of its length, a plunger adapted for longitudinal travel within the tube to propel a lead in advance of itself, an element projecting laterally of the plunger adapted to travel within the groove, means adjacent one end of the groove for guiding the projecting element into cooperating relation therewith, and an actuating member extending to the exterior of the pencil body mounted for rotation therewith, the actuating member and plunger being formed 120 125 130

with co-operating threads whereby rotation of the one causes propulsion of the other, substantially as described.

3. A pencil having in its body lead propelling mechanism, including in combination a tube within the body provided interiorly with means which present a groove for a portion of its length, a plunger adapted for longitudinal travel within the tube 10 to propel a lead in advance of itself, an element projecting laterally of the plunger adapted to travel within the groove, means adjacent one end of the groove for guiding the projecting element into co-operating relation therewith, and means operable exteriorly of the pencil body for actuating the plunger therewithin, substantially as described.

4. In a pencil, the combination of a tubular casing drawn to a taper at one end, a tube within the casing abutting its walls near the extremity of their taper and formed with a shoulder in the region where said taper commences, lead propelling mechanism within the tube adapted to project a lead through the tapered end of the pencil, and a brace plate extending between the tube and casing in abutting relation to the shoulder on the tube, and serving, together with the end of the tube, to determine the position of the latter longitudinally of the casing, substantially as described.

5. A pencil embodying, in combination, a hollow casing, a tube arranged within the casing, lead propelling mechanism within the tube, and a plurality of partition members arranged between the tube and casing, each of the said members consisting of two 40 portions radially disposed and an arc-shaped connecting portion adapted to lie adjacent the inner wall of the casing, substantially as described.

6. In a pencil, the combination with a hollow casing having a tube therewithin in spaced relation to the casing walls, the tube forming an enclosure for a lead propelling mechanism, of a magazine for leads within the space surrounding the tube, the magazine being subdivided into a plurality of chambers by means of sectional partitions each independent of the others and formed of a spring material such that the several partitions are held in place by their own 55 spring action, substantially as described.

7. A pencil embodying, in combination, a hollow casing, a tube arranged within the casing, lead propelling mechanism within the tube, and a plurality of partition members radially arranged between the tube and casing, each of the said members being formed of spring material and adapted to remain in a fixed position within the casing under the influence of its spring action, substantially as described.

8. A pencil having a body closed except at its ends, a hollow member situated centrally of the body, a plunger arranged for travel within the member and adapted to advance a lead into operative position through one end of the pencil, means for retaining an eraser at the opposite end of the pencil, the plunger being reversible in its travel to advance the eraser outwardly from the pencil, means for causing propulsion of the plunger, and a single actuating means exteriorly of the pencil body for propelling the plunger in either direction to thereby advance either the lead or eraser, as desired, substantially as described. 80

9. A pencil having within its body means for advancing into operative position at one end thereof a lead, and into operative position at the opposite end thereof an eraser, and a single actuating means exteriorly of the pencil body for operating the propelling means therewithin, substantially as described. 85

10. A pencil having in its body means for propelling into operative position at one end thereof a lead, and into operative position at the other end thereof an eraser, and a single actuating means therefor situated exteriorly of the body and operable by rotation relative thereto, substantially as described. 90

11. A pencil embodying in combination within its body a combined lead and eraser propelling mechanism adapted to advance a lead through one end of the pencil into operative position, and an eraser at the other, and a single actuating means exteriorly of the pencil body for operating the propelling mechanism whereby either the lead or eraser may be advanced into operative position, substantially as described. 101

12. A pencil equipped with eraser retaining means rotatable with respect to the pencil body, a combined lead and eraser propelling mechanism within the pencil adapted to advance either the lead or eraser, or both, into operative position, and operating means therefor adapted for actuation with rotation of the eraser retaining means, the direction of rotation determining whether it be the lead or eraser that is propelled, substantially as described. 110

13. A pencil in which is movably mounted a lead at one end and an eraser at the other, a means within the pencil body movably interposed between the lead and eraser adapted to advance toward either to effect a propulsion thereof without affecting the other, and actuating means therefor exteriorly of the pencil, substantially as described. 120

14. A pencil in which is movably mounted a lead at one end and an eraser at the other, and a single means for advancing either the lead or eraser into operative posi- 130

tion without affecting the other, substantially as described.

15. A pencil in which is movably mounted a lead at one end and an eraser at the other, and means independent of both the lead and eraser adapted to advance either into operative position, substantially as described.

16. A pencil having within its body lead propelling mechanism and exteriorly of its body, a rotatable eraser holder adapted also to function as an actuating means for the lead propelling means, a plate within the eraser holder having threaded engagement therewith and abutting relation to the eraser therein, the lead propelling mechanism and parts associated with the eraser holder being operatively related to each other so as to produce relative rotation between the plate and eraser holder when the latter is properly rotated, substantially as described.

17. A pencil having within its body lead propelling mechanism and exteriorly of its body a rotatable eraser holder and an eraser therein, said holder being adapted also to function as an actuating means for the lead propelling mechanism, and a plate within the eraser holder having threaded engagement therewith and abutting relation to the eraser therein, the lead propelling mechanism and parts associated with the eraser holder being operatively related to each other so as to hold the plate stationary during rotary movements of the eraser holder in one direction, substantially as described.

18. A pencil having a rotatable head adapted to function as an eraser holder an eraser therein, a plate threaded within the holder in abutting relation to the rear end of the eraser, and propelling means for the eraser adapted to produce relative rotation in one direction only between the eraser holder and plate therewithin, substantially as described.

19. A pencil equipped with eraser retaining means rotatable with respect to the pencil body, a plunger adapted for longitudinal travel within the body, a threaded connection between the eraser retaining means and plunger whereby the latter is propelled upon rotation of the former, a plate movable longitudinally within the eraser retaining means to advance the eraser therewithin, the plunger when moved against the plate being adapted to propel the same together with the eraser for a desired distance, substantially as described.

20. A pencil having on one end a rotatable interiorly threaded eraser retaining sleeve, a plate threaded in the sleeve and adapted to lie behind an eraser therein, a threaded plunger mounted for longitudinal travel, but not for rotation, interiorly of the pencil body, operating means therefor

adapted for actuation when the sleeve is rotated, the plate being formed with a threaded socket into which the plunger end may enter with operation of the parts whereby the plate is prevented from rotating with the sleeve to thereby propel the eraser outwardly, substantially as described.

21. A pencil having on one end a rotatable interiorly threaded eraser retaining sleeve, a plate threaded in the sleeve and adapted to lie behind an eraser therein, a threaded plunger mounted for longitudinal travel but not for rotation interiorly of the pencil body, operating means therefor adapted for actuation when the sleeve is rotated, the plate being formed to lock with the plunger end upon operation of the parts whereby the plate is prevented from rotating with the sleeve to thereby propel the eraser outwardly, substantially as described.

22. A pencil having within its body a lead propelling means adjacent which is a chamber for reserve leads, means extending to the exterior of the body for actuating the lead propelling means, and means independent of the actuating means adapted to detachably maintain the latter operatively within the body and to provide with the actuating means a closure for the reserve lead chamber, substantially as described.

23. A pencil having within its body a lead propelling mechanism, there being a space surrounding said mechanism within the body open at its upper end and forming a circular magazine for reserve leads, and means for actuating the lead propelling mechanism extending to the exterior of the pencil body at its upper end and adapted to overlie the open end of the magazine, and means for detachably securing said actuating means to the pencil body whereby leads within the magazine may be extracted, substantially as described.

24. A pencil having within its body a lead propelling mechanism, there being a space surrounding said mechanism within the body open at one end and forming a circular magazine for reserve leads, and means for actuating the lead propelling mechanism extending to the exterior of the pencil body at the open end of the magazine and adapted to overlie the open end of the magazine, and means for detachably securing said actuating means to the pencil body whereby leads within the magazine may be extracted, substantially as described.

25. A pencil whose body is formed of a hollow casing, a tube immovably secured centrally within the casing, lead propelling mechanism within the tube, there being a space surrounding the tube open at the upper end of the pencil and forming a magazine for reserve leads, and means for actuating the lead propelling mechanism extending to the exterior of the pencil body at its

upper end adapted to overlie the open end of the magazine, and means for detachably securing the said operating means to the pencil body whereby leads may be removed 5 from the magazine, substantially as described.

26. A pencil having in the lower portion of its body a slotted core, and in the upper portion of its body a sleeve mounted for rotation, the core and sleeve being in aligning but not telescoping relation, a plunger adapted for travel through the sleeve and core, there being threads on the sleeve co-operating with threads on the plunger to 10 cause propulsion of the latter with rotation of the former, and an element projecting laterally from the plunger into the slot of the core to hold the plunger against rotation therewithin, substantially as described.

27. A pencil having in one end portion of

its body a sleeve and in another end portion of its body a core, the core and sleeve being in aligning but not telescoping relation, one of said elements being mounted for rotation relative to the other and having a slot 25 formed longitudinally thereof, a plunger adapted for travel through the sleeve and core and having a projecting element adapted to lie within the slot to prevent rotation of the plunger relative to the element in which such slot is formed, there being threads formed on the other element and threads co-operating therewith formed on the plunger whereby relative rotation between the two elements produces longitudinal travel of the plunger, substantially as described. 30 35
